UNITED STATES PATENT OFFICE.

STANISLAS ROUSSEAU, OF ALTON, ILLINOIS, ASSIGNOR TO WESTERN CARTRIDGE COMPANY, OF EAST ALTON, ILLINOIS, A CORPORATION OF DELAWARE.

BULLET FOR HIGH-POWER RIFLES.

Continuation of application Serial No. 482,992, filed July 7, 1921. This application filed September 4, 1923. Serial No. 660,792.

This invention relates to bullets for high power rifles, and more particularly to bullets of that type adapted to expand upon impact. This application is a continuation of S. N. 5 482,992, filed July 7, 1921.

Bullets of the expanding type adapted for sporting rifles, as heretofore made depend for their effect upon the translation of the 10 kinetic energy, due to the velocity of the bullet, into energy used up, or, as it is usually called in this sense, "shock". Accordingly such bullets are formed to spread or assume the form of a mushroom immediately upon impact; a further increase in diameter taking 15 place as the bullet meets with resistance upon its course, until when expanded beneath the hide of an animal, it will have been fully expanded. This, of course, means that the greater part of the energy stored in the 20 bullet will be used up at impact and in making a cruel but superficial wound, while the vitals of the animal will not be reached. The points of such bullets are, therefore, deliberately so formed as to be unstable and 25 so as to spread upon impact, the point being soft, hollow and even slit in order to secure that result. Such points do not, of course, penetrate the hide without deformation, but the very object of their formation is the 30 opposite, namely, to cause the tips to open up and spread.

One of the objects of this invention, therefore, is to provide a bullet for high power rifles which will penetrate without deformation 35 but which after such penetration will expand or distend and even become disrupted.

Another object of this invention is to provide a bullet for high power rifles which 40 will readily penetrate the hide and bone of an animal, but which when reaching the vitals, will expand and become disrupted with great destructive effect.

Another object of this invention is to provide a bullet of the character described whose 45 accuracy is not impaired but even improved and is, therefore, adapted for rifle practice as well as suitable for hunting purposes.

Further objects will appear from the 50 detail description, taken in connection with the accompanying drawing, in which:

Figure 1 is an elevation of a bullet embodying this invention;

Figure 2 is a longitudinal vertical section;

Figure 3 is a longitudinal vertical section 55 showing the bullet after having been fired from a high power rifle, but at a reduced velocity; and

Figure 4 is a view showing the condition 60 of the bullet when fired at high velocity into a soft target, such as the vitals of an animal.

Referring to the accompanying drawing, and more particularly to Figures 1 and 2, the bullet embodying this invention is a 65 jacketed bullet of the type designed for use in high power rifles; accordingly it is pointed and of the usual design, except as hereinafter described. The jacket 1 of copper or copper alloy, contains the core 2 of lead or lead alloy, and this jacket is of sufficient strength to withstand passage through the rifle, at the required high velocity, without splitting, stopping or tearing, while the core, being of lead, or lead alloy, is soft and malleable. The point of the bullet, however, terminates in a slightly blunt tip 3, but if this point were extended as shown in dotted lines, the bullet as a whole would form the 70 outline of a sharp pointed bullet as ordinarily used for high power sporting rifles. 75

Now the point is provided with a cavity 4 which is open at the tip and which extends axially in the core. This cavity is properly proportioned to secure the desired result as hereinafter described; thus for a .30-06 80 Springfield of 150 or 180 grains, a cavity diameter of .055 inch and .375 inch depth 85 have been found suitable. Preferably also the jacket is cannelured as shown at 5, preferably where the point joins or merges into 90 the body of the bullet. It will be particularly noted that the jacket is comparatively heavy, even at the point and tip; accordingly, although the point is hollow and open, it is stable, that is, it is of sufficient stability 95 to penetrate even a solid target, such as the hide of an animal, without mushrooming or deforming; accordingly the bullet has a penetrating point as distinguished from a mushrooming point. 100

The effect and performance of this bullet are striking. Upon referring to Figure 3, which shows the bullet shown in Figures 1 and 2, after having been fired into a soft target, such as the flesh of an animal, but at a reduced velocity, it will be seen, that while the point, and more especially the tip, remains practically undeformed, the base of 105

the point and where it merges into the body of the bullet has become distended; moreover the cavity has become expanded and inflated, both laterally and axially, especially towards the base, while the forward part of the cavity is practically unaltered. In fact it seems that the interior of the cavity, which forms a pocket, has been subjected to an internal pressure causing expansion or inflation of the cavity and therefore distension of the bullet.

Figure 4 shows the bullet of Figures 1 and 2 when fired at high velocity and at close range into a soft target such as the flesh and vitals, as the heart, of an animal. It will be seen that the bullet has become entirely disrupted, and an examination of the fragments shows that the cavity has expanded until the bullet has become so far extended as to disrupt. Now it will be noted that the cannelure 5 provides a weakened section extending circumferentially of the jacket at the point where the greatest expansion takes place, as will be seen in Figure 3. Accordingly the bullet when extended to its limit, will disrupt and tear along the weakened line as shown in Figure 4. It will, however, again be noted that the point and more particularly the tip, is substantially undeformed, except that the driving force of the energy stored in the bullet has somewhat flattened the point laterally, while the jacket part of the body and the core part therein have become totally disrupted and flattened upon further passage through the animal tissues.

While an explanation of the theory of operation is unnecessary, and while this invention is not limited to any particular theory, the following explanation is advanced: When a bullet such as described passes through soft tissues, these will work into the cavity, especially during the rapid rotation of the bullet. There will thus be formed a piston which not only traps the air, already under high pressure, in the pocket thus formed, but the semi-liquid tissues will themselves act hydraulically. These will under the rapidly increasing pressure expand or inflate the pocket in a manner similar to the action taking place when a bottle is blown from the neck. The core is moreover probably in a somewhat plastic state in the body part of the bullet, due to the contact of the body jacket part with the bore of the gun, while the point will be more cool. The result is, therefore, that the cavity is expanded causing extension of the bullet, and where the velocity at impact is sufficiently high, the expansion and extension is carried on until the bullet becomes disrupted or explodes; this disruption is furthermore facilitated by the presence of the cannelure which forms a weak and more easily severed section.

While the bullet embodying this invention becomes distended while passing through soft tissues, such as flesh and blood, and even the hide, no appreciable distension takes place when it is fired into a solid target such as wood or bone. This is probably due to the fact that the hard and fibrous particles of wood or bone, in entering the cavity, become wedged therein, similarly as sand wedges in a pipe; accordingly the expansion of the cavity and the distension of the bullet will be unappreciable; this is borne out by the actual appearance of a cut open bullet so fired. The bullet will, therefore, pass clearly through a solid target.

It will, therefore, be seen that the invention accomplishes its objects. A bullet is provided which is ideal for sporting purposes generally. It is entirely suitable for target practice, since its formation does not detract from its accuracy as is the case with soft nosed bullets. In view of the fact that it has great penetrating power it will pass through bone and other solid obstructions with great effect. It does not flatten upon impact with the hide of an animal, even if tough and thick, but the point being stable will readily pass therethrough. Upon encountering soft tissues, however, it will become expanded and distended, and will even disrupt with a practically explosive action, and with great disruptive effect upon the vitals of the animal, or of the object which it penetrates.

While one embodiment of this invention has been specifically described and illustrated, it will be obvious that this invention is capable of development in other embodiments. It is further obvious that various changes may be made in details without departing from the spirit of this invention; it is, therefore, to be understood that this invention is not to be limited to the specific details shown and described.

Having thus described the invention, what is claimed is:

1. A jacketed bullet for high power sporting rifles having a point of sufficient stability to penetrate the game without mushrooming and which has an open cavity extending back from the tip to provide an expansible pocket adapted to distend the bullet after such penetration.
2. A jacketed bullet for high power sporting rifles having a continuous game penetrating point provided with an open cavity and weakened to expand so as to distend the bullet at the base of the point after such penetration.
3. A jacketed bullet for high power sporting rifles having a stable game penetrating point open at the tip, hollowed rearwardly therefrom and weakened back of the tip, being thereby adapted upon impact to expand back of the tip in order to distend the

bullet at the base of the point after such penetration.

4. A jacketed bullet for high power sporting rifles having a stable game penetrating point provided with a cavity and weakened so as to expand upon impact in order to distend the bullet after such penetration.

5. A jacketed bullet for high power sporting rifles having a stable game penetrating point which has a cavity open to the tip and extending rearwardly to provide a pocket expanding after impact in order to distend the bullet after such penetration.

6. A jacketed bullet for high power rifles whose jacket is weakened back of the tip and having a stable penetrating point provided with a cavity adapted to expand upon impact in order to distend the bullet.

7. A jacketed bullet for high power rifles whose jacket is weakened back of the tip

and having a stable penetrating point which has a cavity open to the tip adapted to provide a pocket expanding upon impact in order to distend the bullet.

8. A jacketed bullet for high power sporting rifles having a point of sufficient stability to penetrate the game without mushrooming and having a cavity extending axially in the core and open at the tip, said cavity being expansible in order to distend the bullet after such penetration.

9. A jacketed bullet for high power rifles whose jacket is weakened back of the tip and having a stable penetrating point provided with a cavity extending axially in the core and open at the tip.

In testimony whereof I affix my signature this 23rd day of August, 1923.

STANISLAS ROUSSEAU.
